[57] CLAIM

The ornamental design for a vehicle roof mounted air conditioner cowling, as shown and described.

DESCRIPTION

FIG. 1 is a side elevational view of a vehicle roof mounted air conditioner cowling showing my new design, the opposite side being a mirror image of the side shown;

FIG. 2 is a top plan view thereof;
FIG. 3 is a bottom plan view thereof;
FIG. 4 is a front elevational view;
FIG. 5 is a rear elevational view thereof; and
FIG. 6 is a front perspective view thereof.
